UNITED STATES PATENT OFFICE

HYMAN SHAPIRO, OF BROOKLYN, NEW YORK, ASSIGNOR TO SAMUEL PERLA, OF
BROOKLYN, NEW YORK

DESIGN FOR AN ILLUMINATED BASE FOR STATUARY AND THE LIKE

Application filed August 5, 1930. Serial No. 36,555. Term of patent 7 years.

To all whom it may concern:

Be it known that I, HYMAN SHAPIRO, a citizen of the United States of America, and a resident of Brooklyn, in the county of Kings and State of New York, have invented a new, original, and ornamental Design for Illuminated Bases for Statuary and the like, of which the following is a specification, reference being had to the accompanying drawings, forming a part hereof.

In the drawings:

Figure 1 is a front view of the illuminated base for statuary and the like;

Figure 2 is a side elevation of the same; and

Figure 3 is a top plan end view of the same, showing my new design, which is characterized by a stepped base portion 1, a platform 2, and a shield 3 to conceal a light source which illuminates the rear panels 4.

I claim:

The ornamental design for an illuminated base for statuary and the like substantially as shown and described.

HYMAN SHAPIRO.
